UNITED STATES PATENT OFFICE

151,274

DESIGN FOR A HOSE REEL

Henry E. Kirschner, St. Joseph, Mo.

Application September 23, 1946, Serial No. 133,498

Term of patent 7 years

(Cl. D91—1)

To all whom it may concern:

Be it known that I, Henry E. Kirschner, a citizen of the United States, residing at St. Joseph, in the county of Buchanan and State of Missouri, have invented a new, original, and ornamental Design for a Hose Reel, of which the following is a specification, reference being had to the accompanying drawing, forming a part thereof.

Figure 1 is a side elevation of a hose reel, showing my new design.

Fig. 2 is a plan view of the hose reel, and
Fig. 3 is a front view thereof.

I claim:

The ornamental design for a hose reel, as shown.

HENRY E. KIRSCHNER.
